UNITED STATES PATENT OFFICE.

JOHN F. WOLVIN, OF ST. CLAIR, MICHIGAN.

BOILER-FURNACE.

1,063,489.

Specification of Letters Patent.

Patented June 3, 1913.

Application filed September 18, 1911. Serial No. 649,924.

To all whom it may concern:

Be it known that I, JOHN F. WOLVIN, a citizen of the United States of America, residing at St. Clair, in the county of St. 5 Clair and State of Michigan, have invented certain new and useful Improvements in Boiler-Furnaces, of which the following is a specification, reference being had therein to the accompanying drawings.

10 This invention relates to improvements in boiler furnaces and its object is to provide a construction especially adapted for burning crushed or powdered fuel, in which a very high degree of efficiency will be secured by the manner in which the fuel and air are introduced into the furnace and by the relative arrangement of the boiler and furnace parts, the invention consisting in the matters hereinafter set forth and more 15 particularly pointed out in the claims, reference being had to the accompanying drawings, in which—

Figure 1 is a longitudinal vertical section through the rear portion of a furnace embodying the invention; Fig. 2 is a similar view through the forward portion of said furnace, portions being broken away to shorten the figure; Fig. 3 is a transverse section of the same on the line 3—3 of Fig. 30 1; Fig. 4, a similar section on the line 4—4 of Fig. 1; Fig. 5, a like section on the line 5—5 of Fig. 2; Fig. 6, a section on the line 6—6; Fig. 7, a section on the line 7—7; and Fig. 8, a front end elevation.

35 As shown in the drawings 1 is a suitable structure formed of brick work, in the forward end of which is an air chamber 2, access to which chamber may be gained through a suitable door 3 in the end wall. 40 Mounted upon this forward end wall is a hopper 4 to receive the fuel which is preferably powdered, crushed or otherwise previously prepared and a feed tube 5 extends through the wall across the upper part of 45 the chamber 2 to conduct the fuel from the hopper. A conveyer screw 6 fitting within the said tube is turned by means of a pulley 7 upon the outer end of its shaft to feed the fuel horizontally from the lower end 50 of the hopper to the inner end of the tube where it drops downwardly through a discharge spout 8 into the upper side of a horizontally disposed feed pipe 9 which is formed funnel shaped with its large end 55 opening rearwardly of the furnace.

Directly to the rear of the air chamber 2

is the tubular fire chamber 10 which opens through a vertical wall 11 into said air chamber 2 and is formed by a wall 12 which is circular in cross section and built up of 60 fire brick or other suitable heat resisting material. Surrounding the wall 12 of the fire chamber is an annular space or air chamber 13 between said wall 12 and the outer circular wall 14 of the structure, which 65 air space communicates with the chamber 2 through a series of holes 13' in said wall 11. The funnel shaped feed pipe 9 is supported with its longitudinal axis coinciding with the axis of the fire chamber and a steam 70 pipe 15 opens into the forward end of the pipe 9 through a suitable restricted end or nozzle 16. The pipe 15 is bent within the chamber 2 and extended rearwardly through the wall 11 and air space 13 close to the wall 75 12 of the fire chamber.

The rear end of the fire chamber 10 opens into an expansion chamber 17 through a vertical division wall and arranged at suitable intervals across the fire chamber near 80 its rear end, are baffles 18 formed of checker brick work and similar baffles 19 extend across the fire chamber intermediate its ends, said baffles 19 being spaced a short distance apart and located at a considerable distance 85 from the baffles 18. The openings in each of these baffles are out of alinement with the openings in the adjacent baffles so that the air and products of combustion are forced to travel in a tortuous path. A supporting wall 20 extending across the rear end of the air space 13 is provided with a series of holes 21 through which air is admitted into the space around the fire chamber from a plurality of small tubular passages 22 formed in the outer circular wall 23 which forms a continuation of the wall 14 and incloses a suitable tubular boiler 24 having its flues 25 extending longitudinally therethrough with their forward ends opening 90 into the expansion chamber 17. A baffle wall 26 extends across the expansion chamber 17 at a short distance from the head of the boiler and this baffle wall is formed mainly of checker brick work to permit the 95 heated air and products of combustion to pass therethrough into the boiler flues. The steam pipe 15 extending rearwardly through the air space 13, passes through one of the holes 21 in the wall 20 and thence upward 100 around the wall 12 of the fire chamber at one side thereof to one of the passages 22

at the top of the wall 23 and thence rearwardly through said passage to the steam dome 24' on the boiler or it may extend to any other suitable source of supply. Live steam is thus conducted through the pipe 15 to the nozzle 16 where it will issue into the fire chamber through the feed pipe 9 with great force carrying the crushed fuel with it. The pipe 15 lies close to the wall 10 of the fire chamber and the steam therein is thus super-heated while on its way to the nozzle.

The air passages 22 in the wall 23 surrounding the boiler, open at their rear ends into an air chamber 27 in the forward end of an air heater 28, comprising an outer cylindrical casing 29 having a forwardly flaring end 30 connected to the rear end of the wall 23 and forming the air chamber 27. This heater also comprises a front head or transverse wall 31 and a rear end wall 32 through which tubular air flues 32 open at their ends, said tubes extending horizontally through the casing with their rear ends open to the atmosphere and their forward ends opening into the chamber 27. Through the several air flues 32, extend tubes 33 of a lesser diameter than the internal diameter of the air flues to leave a narrow passage between said tubes 33 and the walls of the air tubes. The forward ends of the tubes 33 open into a chamber 34 formed within the inclosing wall 23 at the rear end of the boiler by a transverse partition 35, and the rear ends of said tubes open through a header 36, into a bell shaped pipe 37 which is connected at its contracted end to the intake opening in the casing 38 of any suitably constructed suction fan 40 which is driven by a pulley 39 or other suitable means upon its shaft.

In the operation of this furnace the suction created by the fan draws air through the tubes 33 from the chamber 34 and 45 through the boiler flues from the expansion chamber 17 and combustion chamber 10. This strong suction will draw in air through the opening 13' in the wall 11 from the space 13 surrounding the fire chamber and 50 through the air passages 22 opening into the rear end of said space, from the chamber 27 which is supplied by partially heated air entering through the tubes 32. The air to maintain combustion in the fire chamber 55 which is drawn from the air space 13 is therefore heated to a high degree in passing through the heater and around the fire chamber, thus aiding combustion. By taking steam from the steam dome and conducting 60 the same through the passages and air space close to the heated walls, said steam is superheated before it enters the fire chamber and combustion is aided thereby. The force of the steam entering through the nozzle 16 will spread the powdered fuel as it is

blown into the fire chamber and it will at once be ignited and burned, the products of combustion passing rearwardly through the baffles 19 and 18 which serve to thoroughly mix the air and gases and retard their flow 70 so that when they come in contact with the walls and baffles which are heated to a white heat, they will be ignited and burned. Upon entering the chamber 17, the air and gases expand and then come in contact with the baffle 26 so that all combustible elements will be ignited and burned before reaching the boiler flues. By the time the products of combustion have reached the boiler they have been completely consumed and the air is heated 80 to a very high degree which it imparts to the water in the boiler in passing through the flues and in passing from the rear end of the boiler through the tubes 33, the heat is further extracted from the air by the wall of ingoing air surrounding each tube within the air tubes 32. Air at a comparatively low temperature is therefore sucked out by the suction fan, all combustible elements of the fuel having been completely 90 consumed and converted into heat units within the furnace.

Having thus fully described my invention what I claim is:—

1. In a furnace, the combination of a structure having an outer wall and an inner wall spaced from the outer wall and formed circular in cross section to form a longitudinally extending tubular fire chamber, said structure being also formed with an air chamber at its forward end into which the forward end of the fire chamber and air space between said walls open, and an expansion chamber at the rear end of the fire chamber which is of greater diameter than said fire chamber, baffles extending across the fire chamber near the rear end thereof, a tubular boiler inclosed within the structure in longitudinal axial alignment with the fire chamber, a suction device connected to the rear end of the structure to induce a flow of air through the fire chamber and expansion chamber and boiler, a fluid supply pipe within the air chamber at the forward end of the structure opening rearwardly into the forward end of the fire chamber, and means for introducing fuel into the fluid entering through said pipe.

2. In a furnace, the combination of a structure having an outer wall and an inner wall with an air space between said walls, said inner wall being circular in cross section to form a longitudinally extending tubular fire chamber, said structure being also formed with an air chamber at its forward end into which the forward end of the fire chamber and air space open, and a chamber of greater diameter than the diameter of the fire chamber into which the rear end of the fire chamber opens, said outer wall of

the structure surrounding the chamber at the rear of the fire chamber, being formed with air passages opening at their forward ends into the air space between the outer 5 wall and the wall of the fire chamber, a tubular boiler within the structure in longitudinal axial alinement with the said chambers, an air heater at the rear of the boiler comprising a series of air inlet tubes 10 communicating at their forward ends with said air passages in the wall of the structure and a series of outlet tubes extending through the air tubes and communicating at their forward ends with a space into which 15 the rear ends of the boiler flues open, a suction device connected to the rear ends of the outlet tubes, a steam pipe in the air chamber at the forward end of the structure opening rearwardly into the fire chamber 20 and communicating at its opposite end with the boiler, and means for introducing fuel into the forward end of the fire chamber.

3. In a furnace, the combination of a structure having an outer wall and an inner 25 wall which is circular in cross section with an air space between said walls, said inner wall forming a longitudinally extending fire chamber, said structure being formed with an air chamber at its forward end into which 30 the forward end of the fire chamber and air space open and formed with a chamber into which the rear end of the fire chamber opens forming an expansion chamber which is circular in cross section and which is surrounded by an extension of the outer wall 35 of the structure which wall is formed with a series of air passages communicating at their forward ends with the air space surrounding the fire chamber, a tubular boiler 40 surrounded by the extension of the outer wall of the structure formed with the air passages, an air heater at the rear of the boiler having outlet tubes communicating at

their forward ends with the boiler flues and having air tubes communicating at their 45 forward ends with the air passages in the wall of the structure, a suction fan for drawing the air from the outlet tubes, a steam pipe in the air space surrounding the fire chamber and extending into the air chamber 50 at the forward end of the structure with its rearwardly flaring end opening into the forward end of the fire chamber and communicating at its opposite end with the boiler, and means for feeding fuel into the 55 steam entering through said pipe.

4. In a furnace, the combination of a structure having an outer wall, an inner wall forming an air space between them and a longitudinal fire chamber, said structure being also formed with an air chamber at its forward end into which said fire chamber opens and with which said air space is in open communication and with an expansion chamber at the rear of and in axial alinement with said fire chamber, a tubular boiler within the structure in longitudinal alinement with the fire chamber with its tubes opening at their forward ends into said expansion chamber, a plurality of 60 spaced baffles extending across the fire chamber near its rear end, a baffle extending across the expansion chamber adjacent to the forward end of the boiler, a suction device for drawing air from the fire chamber 65 through the expansion chamber and boiler flues, and means opening into the forward end of said fire chamber for blowing fuel into said chamber.

In testimony whereof I affix my signature 80 in presence of two witnesses.
